OUTBOARD MOTOR

Alfred Lesage, Schweinfurt, Germany

Application November 2, 1933, Serial No. 696,303
In Germany November 5, 1932

4 Claims. (Cl. 115—18)

The invention relates to an outboard motor for light boats and more particularly to motors of this class to be fastened by the side of the board of the boat, quickly and readily. According to the invention the motor with all its accessories forms a self-contained block which also comprises the means intended for placing the whole set on a pin-shaped carrier integral with the boat. The fastening means consist in a laterally projecting sleeve enclosing the carrier pin and adapted to be immobilized on the same by a simple attachment such as a bayonet-joint and elastic means. An essential feature of the invention is further the particular arrangement of the several parts of the set on the block so that a good accessibility thereof is secured, and the fact that the motor is horizontal and its longitudinal axis parallel or almost parallel to that of the propeller shaft so that, when the motor is running, any shocks produced are taken up by the thrust of the propeller. Also the system of transmitting the torque from the motor to the propeller shaft and the arrangement provided for water cooling are particularly advantageous.

The drawings represent an out-board motor corresponding to the present invention and in which by way of example

Fig. 1 shows a vertical section through the whole set as taken about the line I—I of Fig. 2, some parts disposed in front of the plane of section being shown by dotted lines,

Fig. 2 shows a section on line II—II of Fig. 1, Fig. 3 is an end view of the motor,

Fig. 4 is a longitudinal section of a modification of the fastening attachment, and

Fig. 5 the corresponding outside view thereof, Figs. 6, 7, and 8 show the end of the fastening attachment in several different positions.

The out-board motor comprises the engine cylinder 4, the crank case 5, a flywheel magnet 6, a starting appliance 7 fastened to the flywheel, the propeller shaft 8, the fuel tank 9 placed above the engine cylinder, a muffler 25 arranged by the side of and directly connected to the motor and a carburetor 10, all these items being combined to a block. From the crank case 5 laterally projects a sleeve 11, the bore of which is intended to be pushed over a pin-shaped or tubular carrier, e. g. a tube 12 with which the hull of the boat is provided, so as to carry the motor set. A clutch 12a is provided between the sleeve 11 and the tube 12, said clutch having one element 13a connected to the outer end of the sleeve 11 and the other element in the form of a flange 13 connected to the tube 12. Between the bottom of

the bore of the sleeve 11 and the end of the carrier 12 there is interposed a spring member 14 by which an elastic union is established between the tube 12 and the sleeve 11. The propeller shaft 8 is arranged transversely to the engine shaft and parallelly to the axis of the engine cylinder 4 its drive being accomplished through the intermediary of a worm or helical gear 15 the reduction ratio of which is one half. The water circulation is secured by holes 16 of the propeller 17 and the hollow shaft 8 while the fresh water is taken up by a trunk 18 which can, unless used, be swung towards the motor about a pivot 19 as shown by dotted lines in Fig. 1.

With this arrangement every part of the outboard motor is readily accessible as the latter is open on all sides and the several parts thereof are easily detachable from one another so that they are susceptible of easy repair or change in case of damage. The attachment provided for fastening the motor to the boat is disposed at a point and designed in a way not interfering with the accessibility of the other parts of the set. Moreover the sleeve 11 is by a carrying yoke 20 connected to union rails 21 fastened to the motor so that the structure is further stiffened.

In the embodiment shown by Figs. 4 and 5 the free end of the sleeve 10' is provided with an enlargement 12' which is to enclose a flange 13' fastened to the carrier 11', e. g. by spot welding. At its front end the enlargement 12' is closed by a lid 14' secured on the said sleeve in any suitable manner. On its outside face the flange 13' is provided with a radial knife-like rib 15' and accordingly the lid 14' carries on its rear face several, e. g. two radial grooves 16' of a similar triangular cross section. The depth of the enlargement 12' is so proportioned that the flange 13' can be pushed inward by the carrier 11' being displaced, in which case the rib 15' leaves the groove 16' and is prepared to enter another groove when the carrier 11' has been turned and so the motor may be adjusted to another inclination. This engagement may be positively maintained by a nut 18' disposed outside the lid 14' on a thread of the carrier tube 11' and pressing the flange 13' firmly against the lid 14'.

The flange 13' is not round but provided with e. g. two sector-shaped projections (Figs. 6, 7, 8) whereas the lid 14' has corresponding recesses 19' through which the projections of the flange 13' can be passed so as to be caused, when the carrier tube 11' has been turned, to bear against the solid portions of the lid 14', the rib 15' being at the same time introduced into one of the 55

grooves 16' which establishes a sort of bayonet-joint by which the parts 13' and 14' are secured not only to each other in a lengthwise direction but also against relative angular displacements.

5 The invention claimed in the present application relates primarily to the means for mounting the motor on the boat. Other novel features illustrated are claimed in my divisional application Serial No. 118,167, filed December 29, 1936.

10 What I claim, is:—

1. In combination with an outboard motor unit, a bearing sleeve attached to said unit, a rod-like member adapted to be secured to the boat and having a bearing fit in the interior of said sleeve, 15 a clutch, one element of which is connected to the outer end of said sleeve, the other element being connected to the rod-like member for interconnecting said rod-like member and said bearing member against relative rotational movement, 20 and a spring in the interior of said sleeve between the outer end of said rod-like member and the inner end of said sleeve for urging the elements of the clutch together and for effecting a flexible axial connection between said sleeve and said 25 rod-like member.

2. In combination with an outboard motor unit, a sleeve fixed to said unit and extending laterally therefrom, a rod-like member adapted to be secured to the boat and having a bearing fit in the 30 interior of said sleeve, said sleeve and said rod-like member being relatively movable axially, a plate at the outer end of said sleeve encircling said rod-like member, a flange extending radially outwardly from said rod-like member and disposed opposite to said plate, said flange and said 35

plate having facing interlocking surfaces, and a member having threaded engagement with said rod-like member for moving said sleeve axially to bring said flange and plate into interlocking engagement against relative rotation.

3. In combination with an outboard motor unit, a rod-like member adapted to be secured to the boat, a bearing sleeve attached to said unit, embracing said rod-like member and movable axially therealong, a clutch, one element of which is connected to said sleeve, the other element being connected to said rod-like member for interconnecting said sleeve and said member against relative rotational movement, and spring means for urging the elements of the clutch together and for effecting a flexible axial connection between said sleeve and said rod-like member.

4. In combination with an outboard motor unit, a sleeve fixed to said unit and extending laterally therefrom, a rod-like member adapted to be secured to the boat and having a bearing fit in the interior of said sleeve, said sleeve and said rod-like member being relatively movable axially, a clutch between said sleeve and said rod-like member and having one element connected to said sleeve and the other element connected to said rod-like member, and an annular member having a threaded engagement with said rod-like member and engaging the clutch element connected to said sleeve for moving said sleeve axially to bring the two clutch elements into interlocking engagement against relative rotation, and for locking said elements in said interlocked position against relative axial and rotational movement.

ALFRED LESAGE. 35
